MANLEY J. CHERRY AND CARL A. BARTH, OF COTTAGE GROVE, OREGON

AUTOMATIC LATCHING DEVICE

Application filed November 25, 1929. Serial No. 409,705.

This invention appertains to improvements in automatic latching devices generally, and more particularly to a type thereof to be employed in connection with sky-line 5 logging systems and the like.

In the operation of logging systems of the class mentioned much trouble and loss of time has heretofore been experienced by reason of the retrograde movement of the 10 load or log carrier on the sky-line, particularly when the line is of necessity disposed on an incline, and which occurs immediately upon the lowering of the load on the carrier to ground and results in making it often exceeding 15 difficult to release the load from the carrier.

Therefore, it is an object of the present invention to provide a latching device which will automatically operate to secure a load 20 or log carrier immediately upon its coming to rest on a sky-line at a desired point of delivery of a load therefrom and to similarly release the carrier for its return movement along the sky-line to point of reload immediately upon the freeing of the load from 25 the carrier and the initiating of such return movement.

Another object of the invention is to provide a latching device of the class set forth 30 which will be entirely automatic in operation, easy to install, durable and efficient in construction and operation, and comparatively inexpensive to manufacture.

With the foregoing and other equally important objects and advantages in view, the invention resides in the certain new and useful combination, construction and arrangement of parts as will be hereinafter 35 more fully described, set forth in the appended claims and illustrated in the accompanying drawings, in which:

Figure 1 is a perspective view of a conventional form of sky-line logging system, showing an application of the improved carrier latching device thereto;

Figure 2 is a side elevation of the latching device and an associated part of a log carrier as they appear when mounted on a sky-line, the latching device being in its position of readiness to secure the carrier against

possible retrograde movement on the sky-line;

Figure 3 is a view similar to that of Figure 2, but showing the latching device operatively engaged with the carrier;

Figure 4 is a vertical longitudinal section through the latching device per se;

Figure 5 is a top plan view of the outer forked end of the latch operating trigger; and

Figure 6 is a front elevation of the latching device and the associated lower portion of the load or log carrier.

Referring to the drawings, wherein like characters of reference designate corresponding parts throughout the several views thereof, the embodiment of the invention, as shown therein by way of example, is constituted in a casing or frame formed of a pair of side walls 10 which are secured in spaced relation at the opposite sides of a housing 11 disposed between the upper edge portions of the same, and a series of spacing sleeves 12 arranged at various points below the housing 11; suitable fastenings, such as bolts 13, being passed through openings formed in the side walls 10 and the bores of the sleeves 12 for the purpose.

The housing 11 may be formed integral with one of the side walls 10 or separately therefrom, but, in any case consists of a top wall which is coextensive with the top edges of the side walls 10 and a front wall 11' depending for a relatively short distance from the forward ends of the top edges aforesaid and between the front vertical side edges of the walls, substantially as is shown in Figure 4.

Mounted within the confines of the housing portion 11 and extending rearwardly from the front end wall 11', is a shoe 14, which is preferably of wood and is retained in position by means of the fastenings or bolts 13 passing between the side walls 10 and through the housing 11. The lower edge of the shoe 14 is preferably grooved, as at 14', lengthwise thereof to seat on a sky-line *a* extending between two fixed points of support *b*, (Figure 1). The lower edge of the housing wall 11' is preferably recessed correspondingly

with the cross-sectional area of the groove 14', in order to give clearance to the sky-line *a* for its proper engagement by the shoe 14, while the rear end of the lower edge of the latter is rounded off, as at 14'', to prevent any abrasion of the sky-line at that point of such engagement.

Disposed between the side walls or plates 10 and in parallel relation to the shoe 14 is a latch member 15, which has its rear end pivoted, as at 16, at a point toward the rear end of the casing and its front end projected well beyond the forward end thereof. This forward end of the latch member 15 is formed to provide a depending shouldered portion or latch 15', which is beveled at its forward side to facilitate its automatic engagement with a keeper 17 carried on the opposed end of a load or log carrier 18, the latter being also supported on the sky-line *a*. One of the spacing sleeves 12 and the associated bolt 13, employed for securing the side walls 10 and the housing 11 together, is positioned toward the front edges of the walls 10 and in a horizontal plane immediately below that of the pivot 16 to support the latch member 15 in the necessary horizontal position of readiness for engagement of the keeper 17 therewith at each approach of the carrier 18.

Depending from an intermediate part of the latch member 15 and extending angularly forward therefrom, between the lower portions of the side walls 10 of the casing is a trigger 19. This trigger is preferably made up of two pieces of strap-iron or the like riveted in the side to side relation, as at 20, with its attached end of substantially Y-form and secured at the extremities thereof to the latch member by rivets or the like 21. The opposite free ends of the pieces or straps are bent outwardly in opposite directions to form a forked end 19', and these bent portions are braced at their outer sides to intermediate points on the trigger 19 by means of the members or rods 22.

In the use of the latching device as thus constructed and arranged, the casing will be straddled over the sky-line *a* well toward one of the supports *b*, in a manner that the groove 14' of the shoe 14 seats thereon, with the hooked end 15' of the latch member 15 directed away from such support. One end of an anchor cable 23, leading from the support *b*, will be attached to the adjacent upper corner of the casing 10 by means of a clevis 24 which is carried by the securing bolt 13 near the corner aforesaid of the casing. With the device in this position, the hook end 15' of the latch 15 will be opposed to the keeper 17 on the carrier 18, which is also supported from the sky-line *a*.

Running from the lower side of the carrier 18 is a main line *c*, which is trained through a fall block 25 and passes therefrom in a direction opposite to that of a haul back

line *d*, the latter having its adjacent end attached to the fall block 25 by means of a clevis or the like *d'*. Depending from the lower side of the fall block 25 is a load attaching line *e*, to the lower end of which the usual log grapple *f* (Figure 1) is carried.

With the parts of the logging system and the latching device as thus cooperatively arranged, and with the carrier 18 held against movement along the sky-line *a*, by having the keeper 17 engaged by the hook end 15' of the latch 15 as during the lowering of a load or log to ground and the loosening of the same from the carrier grapple aforesaid, the latch 15 will be automatically released from the keeper 17 when a pull is exerted on the haul back line *d* by the logging engine. This pull on the haul back line causes the fall block 25 to ride upwardly on the main line *c* and to force against the under side of the forked end 19' of the latch actuating member 19, which raising movement of the latter therewith results in the hook end 15' of the latch member 15 being lifted clear of the keeper 17. During the pull of the haul back line *d*, it will be understood that the main line *c* is held taut so that the necessary riding of the fall block 25 upwardly on the vertical portion thereof will obtain. Upon the return movement of the carrier 18 from the point of taking on a load and toward the latching device 10, the keeper 17 will strike the forward beveled end of the hook end 15' of the latch member and will pass beneath the same to a position at the rear of the shouldered portion thereof, from which position it will serve to again hold the carrier against retrograde movement back along the sky-line *a* during the dropping of a load from the fall block 25.

Without further description, it is thought that the features and advantages of the invention will be readily apparent to those skilled in the art, and it will of course be understood that changes in the form, proportion and minor details of construction may be resorted to, without departing from the spirit of the invention or its scope as claimed.

We claim:

1. A latch device comprising a casing open at its lower side, a latch member pivotally mounted at one end within said casing and having its other end projecting forwardly of the open portion thereof, actuating means depending from said latch member and extending outwardly from the open side of said casing, a keeper adapted to automatically engage with and disengage from said latch member when moved relatively thereto in opposite directions, and means movable in one direction with said keeper for causing said actuating means to move said latch member to released position.

2. A latch device comprising a casing open at its lower side, a suspension shoe with

in the upper side of said casing, a latch member pivotally mounted at an end thereof within said casing and having its other end projecting forwardly of the open portion thereof, actuating means depending in fixed relation to and from said latch member and extending outwardly from the open side of said casing, a keeper adapted to automatically engage with and disengage from said latch member when moved relatively thereto in opposite directions, and means movable in one direction with said keeper for causing said actuating means to move said latch member to released position.

3. A latch device comprising a casing formed of spaced side walls and open at its lower side, a suspension shoe closing the upper side of said casing, a latch member pivotally mounted at an end thereof within said casing and having its other end projecting forwardly of the open portion thereof, actuating means depending angularly in fixed relation with and from said latch member and extending outwardly from the open side of said casing, a keeper adapted to automatically engage with and disengage from said latch member when moved relatively thereto in opposite directions, and means movable in one direction with said keeper for causing said actuating means to move said latch member to released position.

4. A latch device comprising a casing formed of spaced, horizontally elongated side walls and open at its lower side, a suspension shoe coextensive with said side walls and secured in place between the upper edge portions thereof, a latch member pivotally mounted at an end thereof within said casing and having its other end projecting forwardly of the open portion thereof, actuating means depending angularly forward in fixed relation with and from said latch member and extending outwardly from the open side of said casing, a keeper adapted to automatically engage with and disengage from said latch member when moved relatively thereto in opposite directions, and means movable in one direction with said keeper for causing said actuating means to move said latch member to released position.
